GEORGE L. PREBLE, OF LYNN, MASSACHUSETTS

FABRIC PULLING MACHINE

Application filed October 12, 1927. Serial No. 225,718.

This invention relates to a machine for casting tension upon a flexible strip and more specifically to a machine adapted to assist in the manufacture of insoles for welt shoes.

5 My copending application Serial No. 214,229, filed August 20, 1927, discloses a new method of manufacturing reinforced insoles, wherein reinforcing fabric is provided with a permanently plastic, tenaciously adhesive agglutinant which may be applied directly to the leather insole without requiring heating or any other preliminary treatment. Since the heater is dispensed with, it is feasible to use reinforcing strips of various widths 15 to suit various sizes of insoles, thus avoiding unnecessary loss of fabric and affording greater economies in shoe manufacture. While the adhesiveness of the plastic agglutinant may be varied, it is highly desirable 20 and practicable to provide an agglutinant which has strong adhesion; with material of this character, I have found that it requires considerable force to draw a run of coated fabric from a roll of the same due to the firm 25 adhesion existing between the fabric windings in the roll.

The machine presented by this invention is primarily arranged to permit the use of Gem duck or canvas of this character which is 30 highly adhesive and yet to avoid unnecessary tiring of the workman who is applying the reinforcing fabric to the insoles. This mechanism is designed to be responsive to a light pull upon the part of the operator so 35 that the use of the improved reinforcing fabric in conjunction with the machine requires less effort upon the part of the workman than has previously been necessary. The machine is designed to be particularly 40 compact and to be installed as a unit beneath the work bench that is commonly used in applying the fabric to the insoles. The mechanism is so arranged that it cooperates effectively with the sequence of operations necessary to this part of shoe manufacture and is 45 readily used by one who has previously been using the manufacturing operations which are succeeded by the process described in the above-identified application. Thus the present invention permits the workman to take 50

hold of the severed end of the fabric strip and to draw the same lightly whereupon the machine automatically will start operation in order to cast suitable additional tension upon the fabric run that extends from the 55 adhesively coated roll, thereby overcoming the effect of the strong adhesion between the windings of the roll. Consequently only a light pull upon the part of the operator is required in order to bring succeeding portions of the duck strip into a position where they may be cut off and applied to succeeding leather insoles. 60

Heretofore because of the necessity of running the duck or canvas through a heater, it 65 has been impractical to provide insole reinforcing fabric in various widths or readily to change from the use of fabric of one width to the use of fabric of another width during the course of manufacture. The invention 70 disclosed in the above-identified copending application, however, permits the ready interchange of fabric strips of various widths or other characteristics in order to permit economy in the use of reinforcing material. 75 The machine presented herewith is accordingly arranged to be particularly effective in allowing the convenient use of fabric of various widths to suit the particular needs of the operator, thus permitting the use of the 80 narrowest fabric practical for the insoles that are being reinforced.

The above and further objects and advantageous features of the invention will be apparent to those skilled in the art upon a 85 reading of the subjoined description and claims in conjunction with the accompanying drawings, in which:

Fig. 1 is a side elevational view of one embodiment of the machine forming the subject 90 matter of this invention;

Fig. 2 is an end elevation of the same;

Fig. 3 is a detail plan view of an element for catching the fabric when it is released from tension;

Fig. 4 is a section on line 4—4 of Fig. 1; and

Fig. 5 is a sectional detail on line 5—5 of Fig. 1.

A machine of the type exemplified in the 100

accompanying drawings preferably comprises a supporting plate 1 which may carry all of the various component factors of the machine and which accordingly permits the machine to be applied as a unit to the underside of a work bench or table 2 of the type that is commonly used in applying the reinforcing fabric to the insoles. Thus this machine does not require the use of additional floor space.

10 A suitable hanger 4 is provided with a substantially horizontal spindle upon which is rotatably mounted the spider 6. At the outer end of each arm 7 of the spider is a pin 9 rotatably supporting a roll 8 of the adhesively coated fabric. These rolls preferably comprise Gem duck or canvas coated with a permanently plastic, tenaciously adhesive agglutinant and formed into a roll 15 20 25 30 35 40 45 50 55 60 65 70 75 80 85 90 95 100 105 110 115 120 125 130

wherein the adhesive coating upon the inner face of each winding firmly holds the same in engagement with the outer uncoated face of the adjoining winding. Preferably the pins 9 may support rolls 8 which differ in width or in other characteristics, so that any one of the adhesive rolls may be selectively brought to proper position to supply the desired type of reinforcing strip to the person who is reinforcing the leather insoles. For this purpose I provide means designed in general by the numeral 10 in order to lock the spider 6 in its various adjusted positions.

Locking means 10 is shown in greater detail in Fig. 5 and comprises a pin 11 slidably mounted in the recess 12 in the hanger 4. A compression spring 14 is located between the pin and the inner end of the recess so that the pin is yieldably pushed outward. The outer end of the pin accordingly is pressed against the hub of the spider 6 and is adapted to engage any one of the depressions 15 therein, which correspond in number to the number of pins 9 and are so arranged as to hold one of the rolls 8 in proper position. These depressions preferably are provided with an inclined bottom portion to permit ready rotation of the spider 6 in one direction (i. e. anticlockwise, as shown by the curved arrow in Fig. 1), but are provided with side portions parallel to the axis of the spider, which are adapted to engage the pin to prevent rotation of the support 6 in the opposite direction (i. e. clockwise, as viewed in Fig. 1). Thus it is only necessary for the workman to rotate the spider 6 in one direction in order to bring any desired roll into proper relation to the rest of the machine to permit fabric to be drawn therefrom.

60 A friction roller 20 is supported upon a shaft 21 that forms an extension of the axle of worm gear 37. Roller 20 preferably is provided with a peripheral band 24 of material having a comparatively high coefficient of friction, for example soft rubber, and is 65 so arranged in relation to the spider 6 that

the run of fabric from the adjoining adhesive roll 8 may be wrapped about a considerable segmental portion of the peripheral band 24 when fed to the point of use, whereby the friction roll may have an effective frictional engagement with the fabric strip. Pivotally mounted upon the shaft 21 is a yoke or frame 27 which has upwardly projecting arms carrying a transverse roller 28 at their upper extremities. This roller 28 is 70 75 80 85 90 95 100 105 110 115 120 125 130

adapted to receive the fabric as it leaves the roll 20 and cooperates with the same in effecting the engagement of the fabric surface with a segmental portion of the latter, while permitting the strip to be drawn in the general direction of the surface of table 2 by the workman. The lower portion of frame 27 is extended to provide guards 30 which are located at either side of the periphery of roller 20 in order to prevent lateral movement of the fabric from its proper position upon friction roll 20.

A suitable electric motor 35 is arranged to rotate roller 20 in order to cast the desired tension upon the fabric strip leaving the roll 8. This motor may drive the roller 20 through any suitable means, such as the worm 36 and the worm gear 37 which are supported in the gear box 32. Preferably motor 35 is energized through an electrical line that is controlled by a conventional switch factor 38. The switch is operated by a swinging lever 39 which is connected to the frame 27 by a link 40. A suitable tension spring 42 normally draws the upper portion of frame 27 away from the spider 6, i. e. toward the full line position of Fig. 1, in which position the lever 39 is so disposed as to open the motor circuit. The upper portion of frame 27 projects through opening 3 in table 2 so that the roller 28 is located slightly above the surface of this table. When the workman pulls the severed end of the fabric strip, the frame is drawn to the position indicated in dotted lines in Fig. 1, the lever 39 is swung to its switch closing position, motor 35 is started and serves to rotate friction roller 20, which assists in casting tension upon the adhesive-coated fabric and in pulling the same from the roll 8. As soon as the workman releases the end of the strip, the frame 27 is returned to its retracted position under the action of spring 42, and the switch is opened by lever 39. Thereupon the motor is stopped and no further tension is cast upon the fabric strip. In order to prevent the fabric from slipping away from roller 28 and sagging between that portion of the machine and roller 20, I provide a plate 50 having sharpened edge portions or teeth 51 which preferably are adapted to catch the coated face of the fabric and to retain the same against downward movement, it being obvious that the initial tension upon the end of the strip will serve to swing

frame 27 to a position wherein the fabric will be disengaged from member 50.

It is evident that a machine of the character disclosed herewith may be installed in such a position that it does not require additional floor space and may be readily utilized with very little effort upon the part of the operator, thereby tending to aid the efficiency of the latter. The sequence of operations necessary on the part of the workman is very similar to those previously required in reinforcing insoles, so that the new process of insole reinforcement disclosed in my copending application may be readily adopted without even a temporary loss in efficiency. It is obvious that the provision of a plurality of roll supports makes it possible to adapt the machine to the particular requirements of the factory where it is being used. Thus the various rolls may consist of reinforcing fabric of different widths or of other different characteristics, or the support may merely carry several rolls of the same character of fabric, if desired, thus serving to keep a large quantity of the fabric in the most convenient position for the use of the workman. Obviously it is merely necessary to rotate spider 6 in order to bring a new roll of fabric in proper position for use, whereupon the spider 30 will be automatically locked in proper place as soon as tension is cast upon the free end of the fabric strip.

I claim:

1. Apparatus for pulling a run of adhesively coated material from a roll of said material, comprising a friction roll adapted frictionally to engage the run of material, means to impart movement to said friction roll, control means for said first-named means, a rotatable support adapted to hold a plurality of rolls of coated material and to permit rotation of the same, said support being positioned to cause a run of said material to engage a segmental surface of the friction roll, said support being movable to a plurality of positions to supply coated runs of different characteristics to the friction roll and means adapted automatically to lock the support in each of its several positions.
2. A machine of the class described, comprising a support receiving a replaceable roll of fabric having one face adhesively coated, and permitting free rotation of said roll, a friction roll, a movable frame, said friction roll being frictionally engageable with a run of said fabric extending from said replaceable roll, a portion of said frame above said friction roll engaging the uncoated face of the run, said frame being movable in response to tension cast upon said run, driving means for imparting movement to said friction roll, means actuatable by the movement of said frame to control the operation of said driving means, and means to engage said fabric run adjoining said portion of the

frame to prevent the fabric from sagging away from the frame when the tension thereon is released.

3. Apparatus for pulling a run of adhesively coated fabric from a roll of said material comprising a friction roll to engage a run of the material, driving means to rotate said friction roll, control means effective to start and stop operation of the driving means, a swinging frame having a portion to engage the fabric run after engagement with the friction roll, means yieldably to hold said frame in a normally inoperative position, said frame being movable from said inoperative position under tension upon the fabric run engaging said portion of the frame, said control means being arranged to cause operation of the driving means when the frame is swung away from its inoperative position, and a fixed part against which the frame moves the fabric run to hold the fabric run against movement when the frame is in its inoperative position.

4. Apparatus for pulling a run of adhesively coated fabric from a roll of said material comprising a friction roll to engage a run of the material, an axial support for said roll, driving means to rotate said friction roll, control means effective to start and stop operation of the driving means, a frame mounted to swing about the axial support and having a portion remote from that support to engage the fabric run after engagement with the friction roll, and means yieldably to hold said frame in a normally inoperative position, said frame being movable from said inoperative position under tension upon the fabric run engaging said portion of the frame, said control means being arranged to cause operation of the driving means when the frame is swung away from its inoperative position.

5. Apparatus for pulling a run of adhesively coated fabric from a roll of said material comprising a planar support, means associated with the support for supporting a roll of fabric beneath the same, a friction roll disposed below the support to engage a run of the fabric, driving means to rotate said friction roll, control means effective to start and stop operation of the driving means, a swinging frame extending through an opening in the planar support and having a portion to engage the fabric run after engagement with the friction roll, and means yieldably to hold said frame in a normally inoperative position, said frame being movable from the inoperative position under tension upon the fabric run engaging said portion of the frame so that said portion is disposed above the planar support, said control means being arranged to cause operation of the driving means when the frame is swung to a position wherein said portion is above the support.

6. Apparatus for pulling a run of adhesively coated fabric from a roll of said material comprising a planar support, means associated with the support for supporting a roll of fabric beneath the same, a friction roll disposed below the support to engage a run of the fabric, driving means to rotate said friction roll, control means effective to start and stop operation of the driving means, a swinging frame extending through an opening in the planar support and having a portion to engage the fabric run after engagement with the friction roll, means yieldably to hold said frame in a normally inoperative position, said frame being movable from the inoperative position under tension upon the fabric run engaging said portion of the frame so that said portion is disposed above the planar support, said control means being arranged to cause operation of the driving means when the frame is swung to a position wherein said portion is above the support, and a fixed part carried by the support and engageable with the fabric run to hold the latter against movement when the frame is in its inoperative position.

7. Apparatus for pulling a run of adhesively coated fabric from a roll of said material comprising a planar support, means associated with the support for supporting a roll of fabric beneath the same, a friction roll disposed below the support to engage a run of the fabric, driving means to rotate said friction roll, control means effective to start and stop operation of the driving means, a swinging frame extending through an opening in the planar support and having a portion to engage the fabric run after engagement with the friction roll, means yieldably to hold said frame in a normally inoperative position, said frame being movable from the inoperative position under tension upon the fabric run engaging said portion of the frame so that said portion is disposed above the planar support, said control means being arranged to cause operation of the driving means when the frame is swung to a position wherein said portion is above the support, said frame moving the fabric run between said frame portion and the friction roll into engagement with a part at the side of the opening to hold the fabric against movement when the frame is in its inoperative position.

55 Signed by me at Boston, Massachusetts, this 11th day of October 1927.

HORACE M. EATON.
